CIRCUIT BREAKER

William H. Frank and Joseph A. Messing, Detroit, Mich., assignors to Bulldog Electric Products Company, Detroit, Mich., a corporation of West Virginia

Original application March 29, 1934, Serial No. 717,989, now Patent No. 2,035,743, dated March 31, 1936. Divided and this application February 3, 1936, Serial No. 62,139

4 Claims. (Cl. 200—116)

This application relates to circuit breakers and discloses a novel form of breaker. It is a divisional of a prior application, Serial No. 717,989, filed March 29, 1934, now Patent No. 2,035,743, granted March 31, 1936.

Details of the construction shown will be understood upon reference to the following detailed descriptive matter which relates to the appended drawings. In these drawings,

10 Figs. 1-3 show a breaker in top plan, end, and elevational view, and in "on" position;

Figs. 4 and 5 show the breaker in elevational view and in "off" and "overload off" positions, respectively;

15 Figs. 3a, 4a, and 5a are diagrammatic views like Figs. 3, 4, and 5.

The device shown includes a base 60 having a line contact 61 which may be engaged by contact 62 on the end of contact arm 63, and a thermostatic or bimetallic warping element 64, one of whose legs is connected to contact arm 63 by a flexible jumper 65, and the other of whose legs is connected to a load line, as shown.

20 The arm 63 is journalled on pin 66, connecting the upwardly extending frame plates 67 rigidly secured to the base. At 68 the arm is pivotally connected to the lower ends of a pair of links 69, which, at their upper ends, are pivotally connected to the lower ends of links 71, this connection including an axle-pin 72. Links 71 are connected by a pin 73 to an upwardly projecting link 74 which is journalled in the open frame 67 at 75. The circular motion of pin 73 about pin 75 is restricted by its being positioned to ride in an

25 arcuate hill and valley recess 76 in the interior edges of frame plates 67.

Pins 77 in the lower part of the frame journal an operating arm or handle 78 which partially encloses frame 67 and the parts therein contained, 30 and which is surmounted by a manipulating handle 79.

The sides of handle 78 are cut out as shown at 35 81 to clear coiled tension resisting springs 82, whose upper ends are hooked into holes 83 of handle 78 and whose lower ends are hooked around axle pin 72. These springs tend to pull 40 towards the left and upwardly on pin 72, when the parts are at rest, in "on" position, such movement of the pin, together with a corresponding 45 movement of the linkage, being prevented by the pins being positioned in an elongated slot 84 of a link 85, pivotally connected by a pin 86 to a pawl 87, journalled in frame 67 on contact arm journal pin 66, the pawl preventing the linkage, etc., 50 55 from moving.

The right end 88 of the pawl 87 is held down by a shoulder 89 on the warping element 64. The upper left hand end 91 of pawl 87 is pivotally connected, by a pin 92, to an upwardly projecting arm 93, having a curved upper end 94 bearing against link 74, with a constant pressure, created by the compressive action of a spring 95 which is rigidly connected to pin 66 and is pivotally connected to arm 93, at 96. The upper portion 97 of handle 78 is provided with a downwardly projecting striker 10 98 which engages a lug 99 on arm 93 when the latter is in its uppermost position.

The operation of the device is as follows:

Assume the parts to be in "on" position. When the circuit is to be broken, handle 79 is moved to 15 the right, causing the line of action of the springs to be shifted to the right. When the line of action of these springs crosses the links 71, the pull of the spring 82 will collapse the toggle linkage 69 and 71 to the right, thus causing the contact arm 20 63 to snap the contact 62 away from contact 61, effecting a quick rupturing of the circuit. The parts are held at rest in this, the normal "off" position, by the pull of springs 82 and by the fact that parts 69—71 abut frames 67. 25

When the parts are to be moved from the normal "off" to the "on" position, handle 79 is moved to the left. The springs 82 will be moved to the left until they cross the links 71 whereupon they will snap the toggle 69—71 to its "on" or its extreme left hand position where pin 72 engages with the left hand end of the elongated slot 84 in link 85. 30

When the parts are in the "on" position and an overload in the circuit causes element 64 to warp 35 to the right, pawl 87 will be released. This relieves pin 72 for movement to the left and springs 82, pulling up and to the left, will quickly snap pin 72 up and to the left, causing a quick break. Link 74 will be rotated counter-clockwise about 40 pivot 75 forcing pin 73 to snap to the right hand end of the arcuate recess 76 in frame 67. There is thus produced, by all this action, quick-break between contacts 61—62, and all the parts will come to rest in "overload off" position. 45

To reset the device, handle 79 is first moved to the right. When the line of action of the springs 82 crosses the pivots 72 and 73, the pull of these springs will collapse the lower toggle linkage 69—71 to the right. The edges of links 71 engage 50 the end 91 of pawl 87 and rotate it clockwise about pivot 66 until its end 88 passes by and under tongue 89 of element 64. The striker 98 on handle 79 passes over and behind link 93, the latter moving like a pawl about pivot 92 to per- 55

mit the striker to pass behind it. When the handle is then thrown to the left to "on" position, it engages link 93, forcing link 74 to rotate clockwise about pivot 75 until it reaches the "on" position.

5 It will be observed that for a normal switching action the handle 79 is moved towards the right to collapse the major linkage 69-71 with a spring over-center action by moving the knee 72 thereof to the right and thus moving the interrupter 63 out of closed circuit position; and that handle 79 may be moved to the left to straighten the major linkage 69-71 by movement of the knee thereof back to closed circuit position with an over-center spring action and thus moving the interrupter back to closed circuit position.

10 On overload action the circuit current responsive means comprising the pawl 87 collapses the major linkage by moving the knee thereof to the left without such movement being necessarily accompanied by movement of the handle 79; such movement is accelerated by the springs 82 and such movement causes the interrupter 63 to open the circuit; such movement is also accompanied by collapse of the minor linkage 71-74 by movement of the knee 73 thereof to the right.

15 For reset thereafter, handle 79 is moved to the right to reverse the major linkage 69-71; thereafter movement of handle 79 back to the left will reverse the minor linkage 71-74 with the result that after such double motion of the handle 79 both linkages and the parts are left in the closed circuit condition of Fig. 3a.

20 We claim:

25 1. In a circuit breaker, a three link mechanism including two connected toggle linkages having a first end link, a common link, and a second end link, automatically operating circuit responsive

means operable to cause overload release by collapsing one linkage comprising the first end link and the common link and thereafter shifting the second end link and with it the already collapsed linkage, the mechanism being so constructed and arranged as to be resettable by reversing the linkage comprising the common link and the first end link while the second end link is in its shifted position and thereafter reversing the linkage comprising the common link and the second end link and thereafter straightening the linkage comprising the first end link and the common link.

2. A construction of the character described in claim 1 provided with means constantly biasing the first mentioned linkage out of closed circuit position, and a circuit current responsive latch holding the first mentioned linkage in closed circuit position against the influence of the last mentioned means.

3. A construction of the character described in claim 1 provided with means manually operable for causing the collapsing of the first mentioned linkage when it is in its closed circuit position without disturbing the second end link.

4. A construction of the character described in claim 1 provided with means constantly biasing the first mentioned linkage out of closed circuit position, and a circuit current responsive latch holding the first mentioned linkage in closed circuit position against the influence of the last mentioned means, and also provided with means manually operable for causing the collapsing of the first mentioned linkage when it is in its closed circuit position without disturbing the second end link.

JOSEPH A. MESSING.
